VACUUM OPERATED WINDOW REGULATOR

Roy H. Dean, Detroit, Mich., assignor to Ternstedt Manufacturing Company, Detroit, Mich., a corporation of Michigan

Application January 24, 1941, Serial No. 375,710

7 Claims. (Cl. 268—125)

This invention relates to vacuum operated window regulators. Vacuum powered window regulators are old in the art. One of the drawbacks of this system of raising and lowering the windows is that, when the engine stops, the vacuum fails and the windows cannot be operated.

It has already been proposed to provide vacuum storage tanks to furnish a vacuum even when the engine has ceased to operate but these are effective only for a few hours as there are always leaks which tend to equalize the pressures and then the storage tank becomes ineffective. Then, the only way that windows can be raised and lowered is to start the engine or provide an alternative operating handle and suitable gear connections. The latter is undesirable as it involves mechanical complications and expense in providing the necessary mechanism and, furthermore, a handle has to be provided on each door. Body designers and engineers have desired to eliminate some of the control handles on an automobile door as they are quite a problem in getting in the way of the steering mechanism and also the knees of an occupant of the seat. One advantage of the power operated window regulator is that the window regulator handle can, ordinarily, be eliminated.

It is the object of the present invention to provide vacuum power for automatically operating the window regulators and to have this power always available even when the motor has stopped, thus making the windows operable without starting the engine and without providing optional hand operators.

In the drawing:

The figure is largely a diagrammatic view showing the apparatus applied to a front door equipped with the "Fisher No Draft" ventilating system.

1 designates the door which is shown fragmentarily. 2 is the front swinging panel and window opening. 3 is the division pillar in which is guided the vertically sliding glass 4 which is raised and lowered by a lifting arm 5 fulcrumed at 6. Almost any form of window regulator can be used. Here is shown a common form of lifting arm which has a sliding connection in the channel 7 at the bottom of the window. The power arm of the bell crank is pivoted to the end of the piston rod 8 which has a connection at its other end to the piston 9 which is guided in cylinder 10. This cylinder is pivoted at 11 to the front door pillar so that it may accommodate itself to the arc of swing of the power arm of the regulator. A flexible tube 12 connects with the

right hand end of the cylinder and a flexible tube 13 with the left hand end of the cylinder to put these two ends of the cylinder alternately in communication with the source of vacuum or the atmosphere. This is controlled by a valve 14 in valve casing 15. This happens to be shown as a sliding valve but any suitable form of valve to accomplish this purpose may be used.

As shown in the drawing: Tube 12 is in communication with the atmosphere which enters through port 16 in the valve casing and tube 13 is also in communication with the atmosphere through the passageways 17 through the center of the valve which lead from below the valve to above. When the valve stem 18 is pulled up, the piston valve closes the communication of passageways 17 with tube 13 and the vacuum tube 19 is placed in communication with tube 13 by means of the annular groove 20. It is also placed in communication with tube 21 which leads to the diaphragm motor 22. The application of the vacuum to motor 22 causes the two plates 23 of a transom rod type of clutch to release the piston rod 8. At the same time, the vacuum is applied to the right hand side of the piston 9 through tube 13 and the atmosphere to the left hand side. This will cause the piston 9 to travel from the left to the right hand end of the cylinder 10, thereby lifting window 4.

If the valve stem 18 is pushed down from the neutral position shown in the drawing, then first the tube 21 is brought into communication with the vacuum through passageway 24 registering with the annular groove 20 and then tube 12 is brought into communication with the vacuum by the inlet of tube 12 registering with the annular groove 20. The tube 13 now is in communication with the atmosphere by being open to the space in the top of the valve chamber which is in communication with the atmosphere through the passageways 17 to the chamber in the bottom of the valve casing. Hence, now, the vacuum is applied to the left of the piston and the atmosphere to the right. If the piston is in a position towards the right hand end of the cylinder, it will travel to the left of the cylinder and pull the window down.

The conduit 19 leads to engine manifold 25. Another conduit 26 leads to the diaphragm motor 27. When the vacuum in the manifold fails, the diaphragm 28 is pushed to the right by spring 29 closing switch 30 in the motor control circuit 31. The switch is shown closed in the drawing. If valve stem 18 is pushed either down or pulled up, it will contact terminal 32 or 33, thus closing the

circuit to ground through the winding 34 of the solenoid, closing a motor switch 35 and starting the electric motor M which operates vacuum pump P. Hence, when there is not sufficient vacuum in the manifold, an operation of the valve immediately starts the motor and the pump, creating a vacuum to furnish the vacuum to raise or lower the window. When the engine motor is running, the vacuum in the left hand chamber of the diaphragm motor 27 will always keep the diaphragm 28 to the left and the switch stays open so that the motor M is cut out, even though the valve 18 is operated. A check valve 40 keeps the line to the manifold closed when pump P is working. The vacuum operated switch 30 is adjustable.

What I claim is:

1. In a vacuum operated window regulator operated from internal combustion engines, the combination of means for raising and lowering the window, a control therefor which controls both the engine vacuum and the hereinafter-mentioned independent vacuum producer, a vacuum operated motor having a connection with the engine manifold for causing the atmospheric pressure to operate said motor when the control is actuated and means connecting with said vacuum motor for producing a vacuum wholly independent of the engine suction when the vacuum in the manifold becomes ineffective to operate the motor and only when the control is actuated to operate the window regulator.

2. In a vacuum operated window regulator operated from internal combustion engines, the combination of means for raising and lowering the window, a control therefor which controls both the engine vacuum and the hereinafter-mentioned independent vacuum producer, a vacuum operated motor having a connection with the engine manifold for causing the atmospheric pressure to operate the motor when the control is actuated and electrically powered means connecting with said motor for producing a vacuum wholly independent of the engine suction when the vacuum in the manifold becomes ineffective to operate the motor and only when the control is actuated to operate the window regulator.

3. In a vacuum operated window regulator operated by engine suction, the combination of means for raising and lowering the window, a control therefor which controls both the engine vacuum and the hereinafter-mentioned independent vacuum producer, a vacuum operated motor having a connection with the engine manifold for causing atmospheric pressure to operate the motor, means connecting with said motor for producing a vacuum wholly independent of the engine suction when the vacuum in the manifold becomes ineffective to operate the motor and only when the control is actuated to operate the window regulator, and means automatically setting said last mentioned means in operation when the depression in the manifold falls below a given point.

4. In a vacuum operated window regulator operated by engine suction, the combination of

means for raising and lowering the window, a vacuum operated motor having a connection with the engine manifold for causing atmospheric pressure to operate the mechanism, means including an electric motor and pump connecting with said motor for producing a vacuum wholly independent of the engine suction when the vacuum in the manifold becomes ineffective to operate the motor, an electric circuit and vacuum-controlled switch for so controlling the electric motor and a valve for controlling the application of the vacuum, produced in either way, to the motor to raise or lower the window.

5. In a vacuum operated window regulator operated by engine suction, the combination of means for raising and lowering the window, a vacuum operated motor having a connection with the engine manifold for causing atmospheric pressure to operate the mechanism, supplementary means connecting with said motor for producing a vacuum wholly independent of the engine suction when the vacuum in the manifold becomes ineffective to operate the motor, a valve for controlling the application of the vacuum to the motor to raise or lower the window and means for automatically causing the operation of the supplementary means when the vacuum in the manifold becomes ineffective, comprising an electric circuit controlling the operation of said supplementary means and including two switches, one of which is closed when the vacuum from the engine fails and the other is closed when the said valve is operated.

6. In a vacuum operated window regulator operated by engine suction, the combination of a lifting mechanism, a vacuum motor for raising and lowering the window by means of said lifting mechanism, conduits between the vacuum motor and the source of vacuum from the engine, a valve for controlling said conduits to apply the vacuum to either one side or the other of the motor and a pump and electric motor for making connection with the vacuum motor when the vacuum in the engine fails and only when the control is actuated to operate the window regulator.

7. In a vacuum operated window regulator operated by engine suction, the combination of a lifting mechanism, a vacuum motor for raising and lowering the window by means of said lifting mechanism, conduits between the motor and the source of vacuum from the engine, a valve for controlling said conduits to apply the vacuum to either one side or the other of the motor, a pump and electric motor for making connection with the vacuum motor when the vacuum in the engine fails and means for throwing in the operation of the electric motor and the pump comprising an electric circuit with two switches, a vacuum motor for allowing one switch to close when the vacuum in the engine fails and a second switch controlled by the valve when this is moved either to apply the vacuum to one or the other sides of the vacuum motor.
